US0D1095715S

(12) United States Design Patent (10) Patent No.: US D1,095,715 S
(45) Date of Patent: * Sep. 30, 2025

(54) RACQUET FOR GAMES

(71) Applicant: Evosport AB, Piteå (SE)

(72) Inventor: Joacim Bergström, Piteå (SE)

(73) Assignee: Evosport AB, Piteå (SE)

() Term: 15 Years

(21) Appl. No.: 29/909,699

(22) Filed: Aug. 9, 2023

Related U.S. Application Data

(63) Continuation of application No. 29/816,648, filed on Nov. 23, 2021, now Pat. No. Des. 999,309.

(30) Foreign Application Priority Data

May 24, 2021 (EM) 008550883-0002
May 24, 2021 (EM) 008550883-0004
May 24, 2021 (EM) 008550883-0006

(51) LOC (15) Cl. 21-02

(52) U.S. Cl.

USPC D21/729
